UNITED STATES PATENT OFFICE.

LEWIS B. DOMAN, OF EAST SYRACUSE, NEW YORK, ASSIGNOR TO THE AMPHION PIANO PLAYER COMPANY, OF SYRACUSE, NEW YORK, A CORPORATION OF NEW YORK.

PNEUMATIC SELF-PLAYING MUSICAL INSTRUMENT.

1,269,407.

Specification of Letters Patent. Patented June 11, 1918.

Application filed February 14, 1916. Serial No. 78,173.

To all whom it may concern:

Be it known that I, LEWIS B. DOMAN, a citizen of the United States of America, and resident of East Syracuse, in the county of Onondaga, in the State of New York, have invented new and useful Improvements in Pneumatic Self-Playing Musical Instruments, of which the following, taken in connection with the accompanying drawings, is a full, clear, and exact description. This invention relates to certain improvements in pneumatic self-playing musical instruments and more particularly to pedal-operated means for modifying at will the tone or expression of the musical selection being played, and is somewhat similar to that shown in my Patent No. 912,939, issued February 16, 1909, except that in the present application means is provided for preventing excessive resistance or sudden stoppage of the pedals when operated impulsively to produce louder tones or accentuation of particular notes or chords.

In the patent referred to, the tone modulation was produced through the medium of a normally open valve in the connection between the wind-chest and equalizer arranged so as to move toward or to its closed position against the action of its retracting means by increased air tension in the wind-chest produced by sudden or impulsive action of the pumping bellows, the result of which was to cause accentuation of certain notes or chords by cutting out the equalizer and throwing the full force of the pumping bellows into the pneumatic key-action, and in many instances, particularly when only one note-perforation was registered with the corresponding tracker ducts, the air tension in the pumping bellows and wind-chest would greatly exceed that of the vent through such perforation and would thereby produce excessive resistance to the action of the pedals and consequent shock to the operator.

The main object of my present invention is to overcome these objections through the medium of a secondary pneumatic of relatively smaller capacity than that of the equalizer, but in direct communication with the wind-chest in combination with a normally closed valve in the main connection between the wind-chest and equalizer and a comparatively small by-pass around said valve.

Another object is to provide means for varying the size of the by-pass.

Other objects and uses will be brought out in the following description.

The drawing represents a longitudinal vertical sectional view of a pedal-operated wind-inducing device, including the equalizer and my improved means for preventing excessive resistance to the operation of the pedals under impulsive action. 60

The wind-inducing device comprises a wind-chest —1— communicating through a passage —2— with a pumping bellows —3— having its movable side, as —4—, connected by a link —5— to a suitable pedal —6—, 70 whereby the bellows —3— is distended against the action of the usual retracting spring, not shown, by the downward movement of the pedal.

The bellows —3— is provided with suitable ports —7— and a check valve —8— arranged so as to allow the air to leave the bellows when collapsed and to prevent the entrance of air when distended, the port —2— being also provided with a check valve —9— arranged to open when the bellows —3— is distended and to close when it is collapsed, thereby causing the air to be drawn out of the wind-chest —1— and pneumatic key-action, not shown, but connected to the wind-chest by a pipe —10—. 75

An equalizer —11— is secured to one side of the wind-chest —1— and is connected to the interior thereof by a relatively large 80 main port —12— and a relatively smaller by-pass —13—, the equalizer being normally distended by the action of a retracting spring —14—.

The main port —12— is normally closed 85 by a check valve —15— which only opens during the distension of the equalizer by the spring —14— so as to allow said equalizer to assist in withdrawing air from the pneumatic action during the brief interval 100 of retraction of the pumping bellows.

The relatively small by-pass —13— is always open, but is further restricted in size to any degree desired by an adjustable needle valve —16—, the object of the by-pass being to maintain a partial vacuum in the equalizer at all times during the operation of the pumping bellows —3—. 105

A secondary bellows —17— of relatively smaller capacity than the equalizer —11— 110

is connected by an open port —18— to the interior of the wind-chest —1— and is, therefore, under the direct influence of varying degrees of air tension in the wind-chest as determined by the pumping device.

5 The by-pass —13— is much smaller than either the port —18— or pipe —10— so as to render the player action, not shown, sensitively responsive to the slightest variation 10 of air tension in the wind-chest as produced by corresponding variations in the speed or force of action of the pumping device, whereby the tone modulation or expression may be controlled at will solely by a proper 15 manipulation of the pedals.

That is, a slow steady movement of the pedals will produce relatively soft tones or pianissimo effects without appreciably affecting the normal positions of either of the 20 pneumatics —11— or —17—, owing to the resistance of their respective springs —14— and —19—, but as the speed of action of the pedals is gradually increased, the loudness of tone will be correspondingly increased 25 through the varying grades to fortissimo effects, during which action the air may be gradually exhausted from the main equalizer through the restricted passage —13— tending to collapse said equalizer against 30 the action of its spring —14—, which, upon the slightest reduction of air pressure in the wind-chest or action, reacts to distend the equalizer, thereby allowing the valve —15— to open to compensate for the reduction of 35 air tension in the wind-chest and action in case the action of the pumping bellows should be temporarily interrupted.

It is evident, however, that with the restricted passage —13— and without the use 40 of the secondary pneumatic —17—, if the pedals were operated suddenly or impulsively for accenting particular notes or chords, the air tension in the wind-chest and player-action would instantly become 45 so great as to resist further action of the pedals, thereby producing more or less shock to the operator, but in order to overcome this, I have provided the secondary pneumatic —17— with a distending spring 50 —19— of sufficient tension to resist collapse under an air tension below that which is necessary to produce such fortissimo effects.

It, therefore, follows that when the pumping device is operated under sudden impulsive pulses for accenting individual notes or chords, the excessive resistance to the operation of the pumping device would be instantly relieved by withdrawing the air from the secondary pneumatic, which, being 60 of relatively small capacity, does not detract from the force of the increased air tension upon the player-action, it being understood that the accentuation depends upon the quick movement of the pedal and that the 65 secondary pneumatic —17— is distended by

the spring —19— instantly upon the cessation of such movement, and also that the restricted passage —13— is too small to permit any effect of a sudden increase in air tension in the wind-chest and player-action 70 upon the equalizer —11—.

The relative locations of the equalizer and secondary pneumatic with reference to the wind-chest or wind-inducing device is immaterial so long as they are both connected in such manner as to be influenced by the action of the pumping bellows or air tension produced thereby, the spring —19— of the secondary pneumatic constituting means for distending said pneumatic 80 with greater force than that of the air tension necessary to partially collapse the equalizer.

In operation when the pumping device is operated steadily at any rate of speed according to the expression which it is desired to produce, a more or less constant flow of air will take place from the equalizer to the wind-chest tending to collapse the equalizer to a greater or less extent according to the demands made upon the air tension by the player-action, it being understood that in case a considerable number of player pneumatics should be in action at once, the distention of the equalizer by its 95 spring —14— would assist in maintaining the desired degree of air tension by withdrawing the air from the air-chest through the port, —12— and the then open valve —15—.

During this steady operation of the pumping device, the resistance of the spring —19— will prevent the collapse of the secondary pneumatic —17— which serves as a reservoir and auxiliary equalizer in preventing a sudden increase of air tension in the wind-inducing device beyond a certain degree during a sudden depression of the pedals by allowing the air to be drawn therefrom by the increased tension in the wind-chest through the port —18—, thus allowing the pedals to be easily depressed without perceptible shock to the operator whenever it is desired to accent individual notes or chords above the normal expression as controlled by the normal action of the pumping bellows.

What I claim is:

1. In a pneumatic self-playing musical instrument, the combination of a pedal-operated wind-inducing device, a wind-chest having means for communication with a sound-producing action, a tension-equalizer directly connected through a restricted constantly open passage with the wind-chest to permit the tension in the action to be increased over that in the equalizer by sudden or rapid action of the pedals, and a secondary pneumatic in direct constantly open communication with the wind-chest for pre- 130

venting excessive air-tension resistance or shock when the pedals are operated quickly for accenting purposes.

2. In a pneumatic self-playing musical instrument, the combination of a pedal-operated wind-inducing device, a wind-chest having means for communication with a sound-producing action, a tension-equalizer directly connected with the wind-chest through a restricted constantly open passage and through a separate relatively larger passage, a normally closed check valve for the larger passage adapted to open when

the tension in the equalizer exceeds that in the wind-chest, and a secondary pneumatic 15 in direct constantly open communication with the wind-chest for relieving the tension under impulsive action of the pedal for accenting purposes.

In witness whereof I have hereunto set 20 my hand this 11 day of February, 1916.

LEWIS B. DOMAN.
